TENNIS NET

John R. Scherer, El Monte, Calif., assignor to
 Frank M. Guess and Adeline Anna Guess, El
 Monte, Calif.

Application January 8, 1935, Serial No. 857

2 Claims. (Cl. 273—29)

This invention relates to improvements in nets and has particular reference to a net or barrier adapted to be utilized in playing the game of tennis.

5 The principal object of the invention is to provide a net consisting, preferably, of galvanized steel spring wire crimped and interwoven to realize a double strand web, thus effecting a net construction having the characteristics of 10 resiliency, flexibility, attractiveness, economy and safety.

A further object is to provide a net that will retain its original shape, one that will not be affected by weather conditions, a net that affords 15 great visibility in playing the game of tennis, and a net construction that is economical to manufacture, easy to install and comparatively light in weight.

An additional object is to provide in the construction of the net, means in the form of coils, on the ends of the upright or vertical wires, that encompass the supporting cables to permit a 20 backward, forward and lateral movement of said coils to thus reduce to a minimum any chafing effect on the tennis balls that contact the net.

Another object is to provide means for adjusting the net body with relation to its supports to thus assure the necessary degree of tautness in the net body.

30 Other objects and advantages will be apparent during the course of the following description.

In the accompanying drawing forming a part of this specification and in which like numerals are employed to designate like parts throughout 35 the same,

Fig. 1 is a side elevational view of a tennis net constructed in accordance with my invention,

Fig. 2 is an enlarged fragmentary front elevation of the net,

40 Fig. 3 is a plan view of one of the steel lugs or turnbuckles that retain therein the end of one of the supporting cables,

Fig. 4 is a section through the cable taken on the line 4—4 of Fig. 2,

45 Fig. 5 is a horizontal section through a portion of the net and one of the channel members, the view being taken on the line 5—5 of Fig. 2,

Fig. 6 is a transverse vertical section through a portion of the net the view being taken on the line 6—6 of Fig. 2, and

50 Fig. 7 is a similar view through the cable showing a portion of the channel member in elevation, the view being taken on the line 7—7 of Fig. 2.

55 Great annoyance and difficulty have been ex-

perienced in the use of fabric nets, because of their tendency to sag and slip, because of the further fact that moisture causes them to shrink and rot, and further because they stretch and lose their shape. Even in the use of so-called link-chain nets, dissatisfaction has occurred because the nets of this type lack resiliency, are unsightly, cumbersome, exceedingly heavy, difficult of installation and finally interfere with the much desired visibility in playing the game of tennis. To, therefore, produce a net that will overcome the above referred to disadvantages of the fabric net, and to further provide a net that will be more satisfactory and serviceable in every respect than the referred to link-chain net, I have devised the present invention.

In the accompanying drawing wherein for the purpose of illustration is shown a preferred embodiment of my invention, the numerals 8 and 9 indicate conventional posts or standards to which I fasten my improved net, herein designated as a whole by the reference character A. The said net consists of strands of galvanized steel spring wire, the vertical or upright strands being indicated by the numeral 10 and the horizontal strands being designated by the numeral 11. The said strands are crimped as at B and interwoven as at C, to thus realize a lock mesh, which construction makes it impossible to dislodge the wires by hard-glancing drives of the balls, which is an outstanding fault of single strand fabrics. The said upright wires 10 terminate in coils 12 consisting of two complete turns and of a sufficient diameter to thus loosely encompass an upper horizontal cable 13 and a lower horizontal cable 14. This feature of construction permits a backward, forward, as well as lateral movement of the coils when the net is contacted by the tennis balls. At the respective ends of the double strand web there are provided a pair of channel members 15 preferably made of steel that have provided therein an enlarged opening 16 through which the cables 13 and 14 pass and, likewise, a plurality of spaced apertures 17 through which the longitudinal wires 11 enter the channel members and thereafter are firmly and neatly clinched, as is illustrated to advantage in Figs. 5 and 7, to to thus leave no exposed ends which might cause damage. It will be noted that the ends of the supporting cables 13 and 14 are forced into centrally bored lugs or turn-buckles 18 and are securely anchored therein by reducing the size of the holes at three points under high pressure to effect a strong and reliable gripping action on the ends of the cables. Extensions 19 are connected 55

at one end to the eyes 20 of the turn-buckles and are secured at their opposite ends to hook bolts 21 that extend through the supporting posts 8 and 9. The said bolts are threaded at one end and have 5 threadedly mounted thereon nuts 22. The said extensions 19 may be made in various lengths according to the distances between the posts, while the hook bolts and their threaded nuts permit an adjustment of the top and bottom 10 cables to the proper tension.

From the foregoing description considered in connection with the accompanying drawing, it will be obvious that I have devised a metallic net construction wherein the width of the mesh will 15 always remain constant and the height of the net body will be unaffected.

It is to be understood that the form of my invention herewith shown and described is to be taken as a preferred example of the same and 20 that various changes relative to the material, size, shape and arrangement of parts may be resorted to without departing from the spirit of the invention or the scope of the subjoined claims.

Having thus described my invention, I claim:—
25 1. A tennis net comprising an upper and lower

horizontal supporting cable and a spring steel net supported on said cable, said net consisting of a plurality of interwoven vertical and horizontal wires defining a double strand web, the ends of said vertical wires terminating in coils of a greater diameter than the diameter of the cables to permit backward, forward or lateral movement of the coils on said cables, and channel members adapted to fixedly retain therein the ends of the horizontal wires of said net. 5

2. A tennis net comprising a pair of horizontal supporting cables and a spring steel net supported on said cables, said net consisting of a plurality of interwoven, vertical and horizontal wires defining a double strand web, the ends of 10 said vertical wires terminating in coils of a greater diameter than the diameter of the cables to permit backward, forward and lateral movement of the coils on said cables, channel members adapted to fixedly retain therein the ends of the horizontal wires of said net and adapted to receive 15 therein the ends of said cables, and means for adjusting the ends of said cables for varying the height and the tension of said net. 20
